UNITED STATES PATENT OFFICE.

PAUL E. SCHLEICHER, OF CHICAGO, ILLINOIS.

TOP INCLOSURE FOR RADIATORS.

Application filed June 28, 1924. Serial No. 722,973.

To all whom it may concern:

Be it known that I, PAUL EDWARD SCHLEICHER, a citizen of the United States, and a resident of the city of Chicago, in the county of Cook and State of Illinois, have invented certain new and useful Improvements in a Top Inclosure for Radiators; and I do hereby declare that the following is a full, clear, and exact description of the same, reference being had to the accompanying drawings, and to the numerals of reference marked thereon which form a part of this specification.

This invention relates to a radiator cover or top inclosure which is adapted for forming a bench, shelf or table over the radiator and which is designed for the provision of a humidifier positioned upon the top of the radiator.

The invention comprises the novel structure and combinations hereinafter described and more particularly pointed out and defined in the appended claims.

The accompanying drawings illustrate a preferred embodiment of this invention and in these drawings similar reference numerals refer to similar features in the different views.

On the drawings:

Figure 1 is a broken elevational view of a radiator with my cover applied thereto.

Figure 2 is an end elevational view of a radiator with my cover applied thereto.

Figure 3 is a top plan view of the radiator cover.

Figure 4 is an enlarged fragmentary transverse sectional view of the inclosed radiator taken upon the line 4—4 of Figure 5.

Figure 5 is a longitudinal broken sectional view through the radiator cover and humidifier with the radiator shown in elevation.

Figure 6 is an enlarged transverse sectional view upon the line 6—6 of Figure 5 with the humidifier omitted.

Figure 7 is a fragmentary sectional view upon the line 7—7 of Figure 5 with the humidifier omitted.

Figure 8 is an enlarged fragmentary sectional view through the upper part of the cover support or stand.

Referring to the drawings, it will be observed that I have illustrated in connection with my invention, a common three column type of radiator in which the columns 1 are connected by the intermediate pipe sec-

tions 2 and 3. It will however be understood that my invention may be designed for application to any kind or form of radiator.

In the exemplification of this invention, there is shown an inclosure which covers the back and top of the radiator. This inclosure consists of a rear or back sheet 4 of metal or the like having inwardly directed lateral marginal flanges 4^a to which the rear ends of triangular brackets 5 are secured. The front ends of these brackets 5 (Figures 7 and 8) are provided with slots 6 for receiving the reduced and notched ends 7^a of an inverted T bar 7. The T bar 7 is removably interlocked with the brackets 5 by means of the notches in the reduced ends thereof engaging the brackets 5 whereby the brackets are held in proper spaced relation. The T bar may be removed by merely raising the same a sufficient height so that the outer walls of the notches will clear the lower ends of the slots 6, and then spreading the brackets apart. Each bracket 5 is provided with a series of apertures 8 (Figure 7) for a purpose that will later appear. A cover 9 having a filling door 10 fits over the back sheet 4 and end brackets 5 to enclose the top of the radiator and serve as a window seat, table or shelf according to the height and location of the radiator.

This enclosing structure is so designed relative to the radiator, the top of which it is intended to enclose that a suitable space is provided between the cover and the top of the radiator for housing a humidifier 11 which consists of a shallow rectangular pan of water. Suitable supports are anchored to the top of the radiator for sustaining the humidifier and securing the top enclosing structure. In the present embodiment of this invention a pair of end supports and an intermediate support are shown, with the enclosing top for the radiator attached to the end supports.

The type of end support is best shown in Figure 7. It consists of an H shaped base 12 designed to bridge a pair of radiator columns and a rising head 13 provided with a pair of outwardly extending spaced prongs 14 which engage in a pair of the apertures 8 in the brackets 5. The end support also comprises a transverse bar 15 which is provided with a series of apertures for receiving the upper ends of a U bent 16 which engages under the pipe sections 3. This transverse bar 15 extends into abutting

engagement with the back sheet 4 as shown in Figure 4, and serves as a support for the humidifier 11. From an inspection of Figure 7, it is obvious that the H base may be laterally adjusted with respect to its bracket 5 and bar 15 for properly positioning the top inclosure and for fitting different widths of such inclosure.

The intermediate support 17 is best shown in Figure 6. It consists of a shallow V shaped member 17^a having a horizontally extending base 17^b adjustably secured thereto, which spans a pair of the radiator columns and is anchored to the top thereof by a U shaped bolt 16 which engages under the pipe sections 3, and the ends of which engage a transverse bar or strip 18 extending over said base.

It will be appreciated that the enclosing top structure is ornamental as well as useful. It can be designed for application to most common forms of radiators. The provision for the humidifier greatly enhances its value since demands of health require a certain amount of moisture in the air of a dwelling.

I am aware that numerous details of construction may be varied through a wide range without departing from the principles of this invention, and I therefore do not purpose limiting the patent granted, otherwise than necessitated by the prior art.

I claim as my invention:

1. In a radiator cover, a back plate, a pair of brackets attached to the upper side edges of the back plate, a bar removably interlocked with the forward ends of said brackets, interior end supports adjustably connected to said brackets for lateral adjust-

ment with respect thereto, a humidior supported upon said supports, means for clamping said supports upon a radiator and a cover member fitting over said structure. 40

2. In a radiator cover, a back plate, brackets secured to the upper side edges of the back plate, each bracket having a series of holes, a support having prongs adjustably engaging the holes in each bracket, means for clamping said supports upon a radiator, a humidior supported upon said supports, means for holding said brackets in spaced 45 relation and a cover fitting over the tops of said brackets and back plate. 50

3. A radiator cover comprising a back plate, a pair of cantilever brackets secured to the upper side edges of said back plates, 55 each bracket having a slot, and a bar removably confined in said slots against lengthwise movements, a cover member fitting over said brackets and back plate and means for attaching said brackets to the radiator. 60

4. A radiator cover comprising a back plate, brackets connected to the upper side edges of the back plate, a spacing bar removably interengaging the forward ends of said brackets, a cover member fitting over 65 said brackets and back plate and means for adjustably anchoring said brackets to the radiator.

In testimony whereof I have hereunto subscribed my name in the presence of two subscribing witnesses:

PAUL E. SCHLEICHER.

Witnesses:

CARLTON HILL,
CLARENCE SWANSON.
